UNITED STATES PATENT OFFICE.

WILLIAM H. VOSS, OF DAVENPORT, IOWA.

MECHANICAL MOVEMENT.

SPECIFICATION forming part of Letters Patent No. 664,911, dated January 1, 1901.

Application filed September 17, 1900. Serial No. 30,304. (No model.)

To all whom it may concern:

Be it known that I, WILLIAM H. VOSS, a citizen of the United States, and a resident of Davenport, in the county of Scott and State of Iowa, have invented certain new and useful Improvements in Mechanical Movements, of which the following is a full, clear, and exact specification.

The object of my invention is to provide a mechanical movement for windmills, churns, washing-machines, &c., which converts the motion of a continuous-revolving shaft to a shaft arranged substantially at right angles thereto in such manner as to impart to the same a rotary reciprocal movement with a minimum amount of effort and without creating excessive friction. This I accomplish by the means hereinafter fully described and as particularly pointed out in the claims.

20 In the drawings, Figure 1 is a side elevation of my invention. Fig. 2 is a plan view of the same. Fig. 3 is a detail view showing the one position of the pinion in connection with a broken-away portion of the continuously-revolving shaft and the tilting annulus and rack. Fig. 4 is a similar view showing said pinion in another position with relation to said annulus and rack, and Fig. 5 is a vertical longitudinal central section through the 25 rotary reciprocal shaft and mechanism carried by the same separated from the rest of the machine.

In the drawings, A represents a suitable frame having a base-plate or its equivalent, which is screwed or otherwise secured to its support and is provided with arms in which the continuously-revolving shaft B is journaled. One of these arms *a* is extended beyond the bearing of shaft B to form a goose-neck, the end of which is provided with a bearing for the contiguous end of the rotary reciprocal shaft C. Shaft C extends in a plane substantially at right angles to shaft B, although, as will hereinafter more fully appear, it can, to a limited extent, be set oblique thereto. The opposite end of shaft C preferably extends through its bearings and has attached thereto or connected therewith such mechanism as may be desired to utilize 35 the rotary reciprocal motion of said shaft.

At a point on shaft C in alinement with shaft B it has a spheroidal boss *c* keyed there-

to, the top and bottom poles of which are preferably flattened. Surrounding shaft C on both sides of boss *c* are stationary sleeves *d* and *e*, the ends of which next said boss are provided with corresponding convexo-concave bearing-cups *d'* and *e'*, whose edges *x* are so inclined that they approach nearest to each other at diametrically-opposite points 55 intersected by a vertical plane striking through the center of shaft C at right angles to shaft B. From apices thus formed these edges incline in opposite directions at corresponding angles. Surrounding this boss between the bearing-cups *d'* and *e'* is an annulus D, which has a central opening slightly greater in diameter than that of said boss, so as to permit it to move freely upon the same, except as it may be limited by the bearing-cups *d'* and *e'* and by the lugs *f*, projecting 60 radially inward from its central opening into the longitudinal groove *g*, encircling said boss, which latter permits the annulus to have a slight independent vertical tilting 65 movement, but causes it to revolve therewith. 70

The annulus D has the greater portion of its perimeter provided with a segmental rack E, which is constructed of a series of equidistant corresponding radiating bars *h*, projecting 80 from said perimeter, that have their outer ends connected by a surrounding corresponding segmental rim *m*. The perimeter of the annulus from which the bars *h* project is of a width about three times as great as that of 85 the rim *m*, and its ends are rounded in a circular plane struck from the center of the end bars of said rack. Between these rounded ends a guide-block *G* is placed, which, as shown 90 in the drawings, is constructed as though two crescents were placed back to back, with the concaved edges thereof opposite the round ends of the perimeter and concentric therewith.

The end of shaft B extends through the 95 bearing in the arm *a* of frame A and near its extremity is provided with a suitable beveled gear or pinion I, the teeth of which engage the segmental rack substantially as shown. The shaft extends slightly beyond the pinion 100 I toward the shaft C, and the relative width of the perimeter of the annulus and the diameter of the pinion I are such that this extended end *o* of shaft B bears upon the edge

of said perimeter. As pinion I revolves and the annulus is rotated—say from left to right—the end *o* of shaft B when the end of the perimeter approaches the same enters between 5 the projecting horn of the guide-block G and the round end of the perimeter, whereupon the engagement of the teeth of said pinion with the end bar of the rack tilts the contiguous side of said rack, so as to move the 10 same above the pinion and at the same time effects a reversal of the movement of both said rack and annulus and shaft C, by which the same is carried. When the segmental rack and annulus have been moved so that 15 the opposite end of the perimeter thereof approaches the pinion I, the extended end *o* of the shaft B enters the runway between the projecting horn of the guide-block and the curved end of the perimeter and tilts the con- 20 tiguous side of said rack downward and re- verses the movement of the same and said annulus again.

It is apparent that instead of the segmental rack a double row of teeth extending but partially around the perimeter of the annulus might be used. This is an obvious change, and while not illustrating the same I desire to consider as contemplating it within the scope of my invention.

30 From the foregoing explanation of the operation of my invention it is obvious that the segmental rack and annulus are tilted up and down, so as to utilize first the movement of the upper segment of the pinion I traveling 35 in one direction and then the movement of the undermost segment of said pinion while traveling in the opposite direction. The inclining of the edges of the bearing-cups *d*' and *e*' serve to limit the extent of the tilting 40 movement of the segmental rack and annulus; but it is obvious that this feature may be dispensed with and the tilting of the segmental rack and annulus be accomplished in an equally effective manner without the assistance of the same.

45 What I claim as new is—

1. In a mechanical movement the combination with a rotary reciprocal shaft and a tilting segmental rack, of a continuously-revolvable shaft and pinion thereon engaging said rack.
2. In a mechanical movement the combination with a rotary reciprocal shaft, a tilting segmental rack having runways concentric to the ends thereof, of a continuously-revolvable shaft, and pinion thereon engaging said rack said latter shaft having its end extend beyond said pinion and adapted to engage said runway at the ends of said rack.
3. In a mechanical movement, the combination with a rotary reciprocal shaft a boss keyed thereto, a concentric segmental rack connected thereto so as to revolve with said boss, but having a limited tilting movement independent thereof, of a continuously-revolvable shaft, and pinion thereon engaging said rack.

4. In a mechanical movement, the combination with a rotary reciprocal shaft, a spheroidal boss keyed thereto having a longitudinal groove therein, a concentric segmental rack having a radial lug projecting into said groove from the circumference of its central opening, whereby said rack has a limited tilting movement independent of said boss but rotates therewith, of a continuously-revolvable shaft, and pinion thereon engaging said rack.

5. In a mechanical movement the combination with a rotary reciprocal shaft, a segmental rack having a tilting movement thereon and stationary sleeves surrounding said shaft on each side of said rack so constructed as to limit the tilting movement of said rack, of a continuously-revolvable shaft, and pinion thereon engaging said rack.

6. In a mechanical movement the combination with a rotary reciprocal shaft, a boss keyed thereto, a segmental rack having runways concentric to its ends and adapted to revolve with said boss, but having a limited tilting movement independent thereof, of a continuously-revolvable shaft, and pinion thereon engaging said rack; said shaft having its end extend beyond said pinion and adapted to engage said runways at the ends of said rack.

7. In a mechanical movement the combination with a rotary reciprocal shaft, a spheroidal boss keyed thereto having a longitudinal groove therein, a concentric segmental rack having runways concentric to the ends thereof, and having a radial lug projecting into said groove from the circumference of its central opening, whereby said rack has a limited tilting movement independent of said boss but rotates therewith, of a continuously-revolvable shaft, and pinion thereon engaging said rack; said shaft having its end extend beyond said pinion and adapted to engage said runways at the ends of said rack.

8. In a mechanical movement the combination with a rotary reciprocal shaft, a boss keyed thereto and a concentric segmental rack connected to said boss so as to revolve therewith, but having a tilting movement independent of the same, and stationary sleeves surrounding said shaft on each side of said boss which are adapted to limit the tilting movement of said rack of a continuously-revolvable shaft and pinion thereon engaging said rack.

9. In a mechanical movement the combination with a rotary reciprocal shaft, a boss keyed thereto a concentric segmental rack having runways concentric to the ends thereof and adapted to revolve with said boss but having a limited tilting movement independent thereof, of a continuously-revolvable shaft and pinion thereon engaging said rack; said shaft having its end extend beyond said pinion and adapted to engage said runways at the ends of said rack.

10. In a mechanical movement the combination with a rotary reciprocal shaft, a spher-

oidal boss keyed thereto having a longitudinal groove therein, a concentric segmental rack having runways concentric to the ends thereof, and having a radial lug projecting into said groove from the circumference of its central opening whereby said rack has a limited tilting movement independent of said boss, but rotates therewith, of a continuously-revolute shaft, and pinion thereon engaging said rack; said shaft having its end extend beyond said pinion and adapted to engage said runways at the ends of said rack.

11. In a mechanical movement the combination with a rotary reciprocal shaft and a segmental rack comprising a series of radiating corresponding bars projecting from its perimeter arranged at equal distances apart and a rim surrounding and bounding their outer ends, and comprising runways in its perimeter concentric with the end bars of said rack, which said rack has a limited tilting movement on said shaft, of a continuously-revolute shaft and pinion thereon engaging said rack.

12. In a mechanical movement the combination with a rotary reciprocal shaft, and a segmental rack comprising a series of corresponding radial bars projecting from its perimeter, and a rim bounding and connecting the outer rims of said bars, and a guide-block secured to said rack between the ends of said series of bars to form concentric runways therewith, said rack revolving with said shaft but having a limited tilting movement independent thereof, of a continuously-revolute shaft and pinion thereon engaging said rack; said shaft having its end extend beyond said pinion and adapted to engage said runways at the ends of said rack.

13. In a mechanical movement the combination with a rotary reciprocal shaft, a boss keyed thereto having a longitudinal groove therein, a concentric segmental rack having

a radial lug projecting in said groove from the circumference of its central opening, whereby 45 said rack has a limited tilting movement independent of said boss but rotates therewith, said rack comprising a segmental series of corresponding radial bars projecting from the perimeter thereof arranged at equal distances 50 apart, and a rim bounding and connecting said bars, a guide-block carried by said rack and inserted between the ends of said series of bars so as to provide runways concentric therewith of a continuously-revolute shaft, 55 and pinion thereon engaging said rack; said shaft having its end extend beyond said pinion and adapted to engage said runways at the ends of said rack.

14. In a mechanical movement the combination with a rotary reciprocal shaft a spherical boss keyed thereto having a longitudinal groove therein, a concentric segmental rack having a radial lug projecting into said groove from the circumference of its central 65 opening whereby said rack has a limited tilting movement independent of said boss, but rotates therewith, said rack comprising a segmental series of corresponding radial bars projecting from its perimeter and a rim bounding 70 and connecting the outer ends thereof, a guide-block carried by said rack and placed between the ends of said series of bars to form runways concentric therewith and stationary sleeves surrounding said shaft on each side 75 of said boss and so constructed as to limit the tilting movement of the rack, of a continuously-revolute shaft, and pinion thereon engaging said rack; said shaft having its end extend beyond said pinion and adapted to engage 80 said runways at the ends of said rack.
